SHOE

George F. Hendricks, St. Paul, Minn.

Application September 8, 1941, Serial No. 410,022

2 Claims. (Cl. 36—45)

My invention relates to an improvement in shoes, wherein it is desired to provide a shoe having a protective toe portion to prevent the seepage of moisture through this toe portion.

I have found that persons following certain trades are bothered by moisture seeping through the vamp of the shoe. For example plasterers, brick layers, masons, hod carriers, cement workers, and plasterer's helpers are extremely apt to have moist material, such as plaster or cement, drop upon the parts over the toes and toe portions of the shoes. The material forming the shoes absorbs the moisture from the plaster or cement and allows moisture to seep into the shoes. I have found that plasterers wearing shoes of the ordinary type usually have damp or moist feet after working a short period of time. Attempts have been made to wear rubbers, or waterproof shoes, but such shoes do not permit the passage of air therethrough and have been found injurious to the feet, when constantly worn. As a result, most persons using plaster or cement prefer to have damp or moist feet than to wear rubbers or moistureproof shoes which do not permit the entrance of air. I have also found my shoes particularly useful for workers in packing houses and the like, where moisture is constantly draining upon the toes of the shoes.

It is the object of my invention to provide a shoe which may be used by plasterers, brick layers, masons, and the like, which will obviate this former difficulty. It is the purpose of my invention to cover a portion of the shoe, such as the vamp of the shoe, with a rubber or other waterproof coating material to prevent moisture from seeping through the leather of which the shoe is formed. Such a construction has certain advantages which are not found in any shoe with which I am familiar. A shoe of this type will not absorb moisture from plaster, cement, or the like, dropping upon the toe portion of the shoe, and yet will not prevent circulation of air through the shoe. As the rubber or waterproof covering extends only over the vamp of the shoe in the forward portion of the shoe body, the remainder of the shoe remains somewhat porous and pliant to permit the necessary air to circulate about the feet.

An object of the present invention is to provide a layer of waterproof material, such as rubber, extending over the vamp of the shoe and extending only throughout the forwardly projecting portion of the shoe, which will prevent moisture from soaking through this portion of the shoe. As most of the cement or plaster

dropping upon the shoes will lodge on this forward portion of the shoe, no seepage of moisture into the body is permitted.

A further feature of the present invention lies in the provision of a moistureproof covering extending over the vamp of the body and which may be anchored marginally to the sole of the body and other shoe body. As all of the edges of the waterproof covering are anchored securely to the body, no moisture can seep beneath this covering and accordingly through the vamp of the body.

A further feature of the present invention resides in the attachment of the waterproof covering in overlapping relation to the attached portions of the shoe top and tongue so that the body top and tongue overly the adjacent marginal edge of the waterproof covering. By this attachment the seepage of moisture around the end 20 of the covering sheet is substantially obviated.

A further feature of the present invention resides in the fact that the waterproof covering member may be attached to a shoe after the shoe has been constructed or may be attached during the manufacture of the shoe. Thus persons who do not care to purchase a new pair of shoes embodying the present invention may have their shoes equipped with the rubber covering made for this purpose.

30 These and other objects and novel features of my invention will be more clearly and fully set forth in the following specification and claims.

In the drawing forming a part of my specification:

35 Figure 1 is a perspective view of a shoe embodying my invention.

Figure 2 is a cross-sectional view through the toe of the shoe illustrated in Figure 1.

Figure 3 is a cross-sectional view showing the 40 attachment between the shoe tongue and the vamp covering for the shoe.

Figure 4 is a perspective view of a modified form of construction.

45 Figure 5 is a cross-sectional view through the modified construction illustrated in Figure 4 of the drawing.

The shoe A is formed in any suitable manner having a sole 10, a heel 11, a vamp 12 forming the toe covering portion of the shoe and including the toe cap, if such a cap is provided. The quarter 13 of the shoe A is secured in the usual manner to the sole 10 and is split at 14, as is usual practice, to provide a pair of lacing edges

15. A tongue 16 is secured to the vamp 12 of the body and to the quarter 13 so as to form a closure

between the lacing strips or flaps 15. All of this construction is common practice.

Extending over the vamp 12 I provide a waterproof covering 17 which forms the basis of the present invention. This covering 17 is provided with marginal edges 19 which extend beneath the marginal edges 20 of the vamp 12 and as best illustrated in Figure 2 of the drawing, stitching 21, or other suitable means may attach the vamp 12 and covering 17 to the sole 10. An inner sole or lining 22 is arranged in overlapping relation with the marginal edges 20 of the vamp 12 and the marginal edges 19 of the covering 17 so as to form a continuous surface upon which the foot may rest.

The covering 17 is attached between the vamp 12 and the sole 10 marginally, and extends rearwardly to the point of attachment between the vamp 12 and the quarter 13. As is best illustrated in Figure 1 of the drawing the vamp 12 is arranged in underlapping relation with the edges 23 of the quarter 13, and the covering 17, being contiguous with the vamp 12 and therefore underlapping the edges 23, is interposed between the vamp 12 and the edge of the quarter 13. Rows of stitching 24 may secure these parts in overlapping relation with the edge of the covering member 17 spaced inwardly of the stitching.

In order to improve the effectiveness of the seal between the shoe and the covering 17, the lower edge 25 of the tongue 16 is arranged in overlapping relation to the covering member 17 and the vamp 12, and is secured thereto by rows of stitching 26. Thus no moisture can seep between the edge of the covering 17 and the vamp 12, as these edges are positioned within the body of the shoe. The manner in which the tongue 16 overlaps the vamp and covering is best illustrated in Figure 3 of the drawing.

In Figures 4 and 5 of the drawing, I disclose a modified form of shoe construction. In this construction I disclose a shoe sole 27 and heel 29 to which are attached the shoe quarter 30 and vamp 31. The quarter 30 is ordinarily secured marginally to the vamp 31 and is secured to the sole of the shoe in any suitable manner. The marginal edges of the vamp 31 are preferably turned inwardly, as indicated at 32 and are held in place by stitching 33, or other suitable means. An insole or lining 34 overlies the sole 27 and the marginal edges 32 of the vamp 31 so as to form a continuous surface upon which the foot may rest.

A covering 35 overlies the vamp 31 and is secured marginally to the sole 27. In this form of construction the marginal edge 36 of the covering 35 is bent outwardly and an anchoring strip 37 overlies this marginal edge 36. Stitching 39 extends through the anchoring strip 37, the marginal edge 36, and the sole 27 to hold these parts 60

in assembled relation. It is difficult for moisture to seep between the edge 36 and the sole 27 to pass into the body of the shoe in this manner.

The rear edge of the covering 35 is secured to the forward edge 38 of the top 30 by means of stitching 40 or other suitable means. A tongue 41 is secured to the vamp 31 by stitching 42 and the lower edge 43 of the tongue 41 overlaps the covering 35 so as to prevent the seepage of moisture about the end of the covering. The covering 35 may be purchased separately and secured to a shoe by a shoemaker or shoe repair man.

I am familiar with the fact that shoes having double toe caps or forward portions have previously been used for the purpose of insulation. In other words, additional covering elements of leather have been used over the forward portions of the shoe in order to make the shoes more resistant to heat. These previous constructions would not serve my purpose, as the rear edge of the covering portion of each shoe was usually free to permit circulation of air, and as the covering portion was formed of material no more waterproof than the vamp itself. On the other hand, while the use of a waterproof covering, such as 17, might act to some extent to resist heat, the waterproof material usually used would not be desirable for withstanding high temperatures. Accordingly, I believe the present construction would be advantageous over previous constructions for its prescribed use.

In accordance with the patent statutes, I have described the principles of construction and operation of my shoe, and while I have endeavored to set forth the best embodiments thereof, I desire to have it understood that obvious changes may be made within the scope of the following claims without departing from the spirit of my invention.

I claim:

1. A shoe comprising a sole, a vamp secured to said sole, a quarter secured to said vamp and sole, a tongue secured to said vamp, and a covering extending over said vamp, said covering being marginally secured to said sole and extending in underlapping relation with the quarter and tongue, the marginal edges of said quarter and tongue overlying the marginal edge of the covering.

2. A shoe comprising a sole, a vamp secured to said sole, a quarter secured to said sole and having a forward edge overlying and extending in overlapping relation to said vamp, a tongue secured to said vamp in overlapping and overlying relation thereto, and a waterproof covering contiguous with said vamp marginally secured to said sole and stitched between said vamp and said forward edge of said quarter, and between said vamp and the overlapping edge of said tongue.

GEORGE F. HENDRICKS.
